UNITED STATES PATENT OFFICE.

JOHAN SKATTEBOE, OF NORDSTRANDSHOIDEN, NEAR CHRISTIANIA, NORWAY.

APPARATUS FOR AND METHOD OF PRODUCING CAST-METAL CHAINS.

Application filed June 3, 1920. Serial No. 386,405.

To all whom it may concern:

Be it known that I, JOHAN SKATTEBOE, a subject of the King of Norway, residing at Nordstrandshoiden, near Christiania, Norway, have invented certain new and useful Improvements in Apparatus for and Methods of Producing Cast-Metal Chains, of which the following is a specification, reference being had therein to the accompanying drawing.

This invention relates to a machine for producing cast metal chains, and embodies sectionalized boxes which, after the pressing operation, are separated after having been removed from the machine, the novel feature consisting in that the mold sand, while pressing, is cut free by thin sheet metal plates, which extend centrally through the cast and are secured between the joints of the mold parts. These sheet metal plates support the sharp edges of the mold and prevent injury thereto when the box is to be removed from the machine. Another feature is the provision of three mold parts, two with square and one with rectilinear cross section.

The machine has the great advantage that the mold is only pressed by the plunger, whereby the care of the machine is extremely simple and easy. Furthermore, links may be produced with a machine which connect the mold boxes and may be inserted in cold condition without making changes necessary.

The drawings disclose an embodiment of the machine. In said drawings:—

Fig. 1 is a top plan view of the machine, but without mold box, pressure block and vertical chain link pattern.

Fig. 2 is a vertical section taken on the line A—A of Fig. 1, with the mold box, pressure block and vertical chain link pattern.

Fig. 3 is a side view.

Fig. 4 is a top plan view of the pressure block with the vertical chain link patterns in dotted lines.

Fig. 5 shows two ready mold boxes in plan view which are arranged serially and ready for casting.

Fig. 6 is a section on line B—B of Fig. 5.

Fig. 7 is a side view of a mold box.

Fig. 8 is a perspective view of the entire machine, the mold box being removed.

The machine comprises two standards 1,

with side pieces 2 secured thereto, which receive the platen 3 on which the chain link patterns 4 and the gate 5 are arranged. To the platen 3, rods 6 are secured, which are secured to the crank shaft 9 by means of crank arms 9^a and links 8, said rods being guided in guides 7. To secure against lateral displacement, the crank shaft 9 is provided with a stop ring 10 on one side of the standard 1, and with a hand lever 11 on the other side of said standard. By means of the hand lever 11 the platen 3 may be raised and lowered. The platen 12 on which two sets of vertical patterns 13 and 14 are secured, is raised or lowered by the rotation of the hand lever 15, the shaft 16, and rods 17, after the cotter 24 has been removed, said rods being provided with studs 17^a which operate in slots 17^b of said levers 15 which are secured to said shaft. The platen 12 is formed at one end (see Fig. 4) so that it may be rotated about the axis 18^a after the nuts 18 have been loosened (Fig. 8). Each half part of the mold box consists of three parts 19, 19 and 20 (Figs. 3 and 5)—outer parts 19, 19; central part 20. In the groove formed by the projecting parts 21 of the box the plates 27 are arranged. The vertical sets of chain link patterns 13 and 14 are provided toward the center, partly with a groove 28. When the platen 12 with the vertical patterns are lowered upon the box parts 19 and 20, the plates 27 enter the groove 28.

If the machine is utilized at first the nuts 18 are loosened and the cotter pin 24 is removed. Thereupon the platen 12, on which the two sets of vertical patterns are arranged, is raised by lowering the hand lever 15. The platen 12 may then be rotated laterally about the axis 18^a in view of its construction as shown in Fig. 4. Thereupon the platen 3 is forced downwardly by means of the lever 11. Sand is then introduced until it reaches the level of the top of the members 2, and thereafter the three box parts 19 and 20 with the sheet metal plates 27 provided between the projections 21 are arranged on the machine in such manner that the pins 25 of the mold members 19 enter the openings 26 of lugs on the sides of the members 2. The platen 12 is turned and secured in position. The box parts 19 and 20 are lowered and secured by means of the cotter pin 24 and nuts 18; thereby the mold box is secured in the machine. There-

upon the box is pressed by rotation of the lever 11 into the position shown in Fig. 3. The mold box is thus only pressed by the platens while simultaneously the sand during the pressing is cut through by the plates 27. Thereafter the platen 12 together with the vertical chain link patterns 13 and 14, is raised by means of the lever 15 after the nuts 18 have been loosened and the cotter pins 24 removed. The vertical chain link patterns 13, 14 are withdrawn vertically from the platen 3. The platen 12 having been raised to the required extent the mold box may then be removed in the usual manner. The plates 27 are removed, whereby the box has been subdivided into three parts 19 and 20.

The single links 22 which are arranged between the upper and lower halves of the box are previously cast chain links, introduced in cold condition, they having been formed in identical manner with the exception that the plates 27 are not arranged in position, because it is not necessary to employ sectionalized boxes for the casting of the single links 22.

After a large number of sectionalized boxes have been pressed and dried they are assembled in continuous lengths of about 28 meters in the following manner:—At first the two parts 19 are assembled (Fig. 6); thereupon the first cast links 22, then the parts 20, thereupon again the links 22, and finally the two latter mold parts 19 are introduced (Fig. 5). Each form box is thus composed of six parts; the members indicated by the dotted lines are cast through the inlet channel 23, while the other links 22 are introduced cold.

Having now particularly described and ascertained the nature of my said invention and in what manner the same is to be performed, I declare that what I claim is:—

1. In a machine for making sand molds for use in the continuous casting of chains, a lower platen, adapted for the arrangement of horizontal chain link patterns thereon, an upper platen, means for raising and lowering said platens at will, means to secure the upper platen against vertical movement, a mold box comprising separable sections having opposed open sides between which vertical chain link patterns may be arranged, and means operative when the platens are moved toward each other, to cut through the sand in the mold box at points coincident with the opposed open sides of the sections thereof, to separate the molds.

2. In a machine for making sand molds for use in the continuous casting of chains, a lower platen, adapted for the arrangement of horizontal chain link patterns thereon, an upper platen, means for raising and lowering said platens at will, means to secure

the upper platen against vertical movement, a mold box comprising separable sections having opposed open sides between which vertical chain link patterns may be arranged, and means operative when the platens are moved toward each other, to cut through the sand in the mold box at points coincident with the opposed open sides of the sections thereof, to separate the molds, the means for raising and lowering the upper platen being independent of the means for raising and lowering the lower platen.

3. In a machine for making sand molds for use in the continuous casting of chains, a lower platen, adapted for the arrangement of horizontal chain link patterns thereon, an upper platen, means for raising and lowering said platens at will, means to secure the upper platen against vertical movement, a mold box comprising separable sections having opposed open sides between which vertical chain link patterns may be arranged, and means, operative by the movement of one of the platens when the platens are moved toward each other, to cut through the sand in the mold box at points coincident with the opposed open sides of the sections thereof, to separate the molds.

4. In a machine for making sand molds for use in the continuous casting of chains, a lower platen, adapted for the arrangement of horizontal chain link patterns thereon, an upper platen mounted for vertical movement and also for swinging lateral movement, means for raising and lowering said platens at will, means to secure the upper platen against vertical movement, a mold box comprising separable sections having opposed open sides between which vertical chain link patterns may be arranged, and means, operative when the platens are moved toward each other, to cut through the sand in the mold box at points coincident with the opposed open sides of the sections thereof, to separate the molds.

5. The process of making sand molds for use in the continuous casting of chains, consisting in placing horizontal chain link patterns at the bottom of a mold box, and forming sand molds in sections in the box, separable on vertical lines and arranged in their opposing sides for the reception of vertical chain link patterns.

6. The process of making sand molds for use in the continuous casting of chains, consisting in placing horizontal chain link patterns at the bottom of a mold box, and forming said molds in sections in the box, separable on vertical lines and arranged in their opposing sides for the reception of vertical chain link patterns, and finally separating said sectional molds on said lines.

In testimony whereof I affix my signature.
JOHAN SKATTEBOE.
